UNITED STATES PATENT OFFICE.

CHARLES LA DOW, OF ALBANY, NEW YORK.

DESIGN FOR A HARROW.

SPECIFICATION forming part of Design No. 19,321, dated September 24, 1889.

Application filed June 7, 1889. Serial No. 318,509. Term of patent 14 years.

To all whom it may concern:

Be it known that I, CHARLES LA DOW, of Albany, in the county of Albany and State of New York, have invented and produced a new and original Design for Harrows, of which the following is a specification.

The drawing is a plan view showing the design, which consists in a new shape for harrows.

10 The leading features are:

First. The zigzag lines formed by the frame-bars having the alternately reversely-inclined parts or lines *a*, connected by intermediate portions *b*, which are in or about in line with the direction of draft of the harrow, in connection with the lines or curved arched figures *C*, formed by the harrow-teeth projecting into the openings *X Y*. The pairs of openings *X X Y Y* each present a figure 15 of somewhat hour-glass shape. The adjacent lines *b* are not in the drawing shown as close together or in contact as they might be, but are separated by a space sufficiently wide to accommodate the harrow-teeth.

Second. The general heart shape of the 25 harrow in connection with the openings *X X Y Y* and figures *C*.

Third. The openings *X X Y Y* in connection with the two central openings of approximately-triangular shape and the irregularly-shaped opening at the front center of the harrow.

Fourth. The openings *X X Y Y* and notches in the adjacent faces of the parts *b*.

The harrow-teeth have in the drawing been 35 omitted from one-half of the frame.

I claim—

The design for a harrow, substantially as herein described and illustrated.

In testimony whereof I have hereunto sub- 40 scribed my name.

CHARLES LA DOW.
